JOHN ERNEST GROSVENOR, OF CHADDESLY CORBETT, AND WILLIAM THOMAS PICKING, OF KIDDERMINSTER, ENGLAND.

SHEDDING AND SHUTTLE-ACTUATING MECHANISM FOR LOOMS.

Application filed December 13, 1923, Serial No. 680,398, and in Great Britain December 23, 1922.

In the production of certain kinds of woven fabrics wherein the ground or body is of considerable weight or thickness, as for example is the case in pile, loop and other

- 5 types of carpet, great strain is put upon the warp operating mechanism through which a large amount of power has to be exerted in raising and depressing the threads of warp which form the pile and body of the fabric.
- 10 To obviate these undesirable and comparatively expensive disadvantages, by the employment of means and following the method hereinafter explained (by following which we dispense with all the shedding movements of the warp threads except those which form the binding chain of warp and the pile, loop or pattern part of the fabric) is the object of our present invention.
- 15 In the accompanying sheets of drawings

20 which are illustrative of our invention:—

Fig. 1 shows the warp threads with the central and pile warps in the positions required to carry out our invention. The two shuttles which we use are shown as passing between the upper and lower warp threads and above and below the central warp threads, each shuttle having a cross sectional contour that meets the requirements of the path through which it has to travel.

30 Fig. 2 is a similar view to Fig. 1, but illustrates a shuttle above the central warp threads, which shuttle is of the same cross sectional contour as the one for passing below said threads. We are enabled to make 35 use of this form of shuttle by the employment of means hereinafter explained.

Fig. 3 is a similar view to Fig. 2 showing the same form of shuttle but passing below the central threads.

40 Fig. 4 is an elevation showing a cam of the type used for operating the warp threads in manner hereinafter described.

Fig. 5 is a front elevation of sufficient of the motor parts of a loom to show the application thereto of our improved devices.

45 Fig. 6 is a plan of the shuttle boxes and a portion of the slayboard or lay bottom, said shuttle boxes having our improved parts added thereto as is hereinafter explained.

50 Fig. 7 is a sectional end elevation, taken substantially on line A—B of Fig. 6, certain parts being added thereto for operating the picker.

55 Fig. 8 is a sectional end elevation, substantially on the line C—D of Fig. 6 and

shows shuttle boxes from which the shuttles are thrown to pass through the two sheds of warp arranged according to our invention.

Fig. 9 is a drawing in detail of a member 60 which we employ for raising and lowering the picker to carry same from being in alignment with one shuttle race or path to be in alignment with the other shuttle race.

A indicates the end frame of the loom and 65 B the slayboard or lay bottom of said loom.

To attain the object of our invention we make use of means whereby those of the warp threads 2 which form the body of the fabric and which have only to be bound or 70 woven into same by the interweaving of the binding warp 3 (or if a pile or loop carpet is being produced of the pile or loop warp 4) may remain stationary or in a central 75 position. That is to say the warp threads 2 according to our method have no shedding or treading motion transmitted to them. The warp threads 4 are only raised from their central positions (where they are 80 parallel to the stationary threads 2) at such times as the pattern of the fabric requires and as is carried out under the actions of the jacquard. While the binding warp threads 3 are alone raised above and carried 85 below the central position.

The warp threads 4 when in their central positions act in conjunction with the warp threads 2 to form the race for the upper shuttle 5.

In following the method of weaving shown 90 in Fig. 1 the binding warp threads 3 are preferably operated by two cams or tappets 6 each of the character shown by Fig. 4, rotating in the direction indicated by arrow α^1 , Fig. 4 and so coupled that when the runner or tappet bowl operating one of the said binding warp threads is in contact with part *c* of the first cam, the runner operating the other binding warp thread is in contact with part *f* of the second cam. The arrangement is such that when the cams are so placed the one binding warp thread is in the central position in alignment with the stuffer or body warp thread and the other binding warp thread is depressed below this point opening the shed beneath the central warp threads ready for the insertion of the bottom shot of weft. The cams revolve so that the first runner comes into contact with part *c* of the cam thereby raising the correspond- 100 105 110

ing binding warp thread from the central to the upper position while the second runner comes into contact with part *f* of the second cam thereby raising the corresponding 5 binding warp thread from the lower to the central position thus opening the shed above the central warp threads ready for the insertion of an upper shot of weft. The first runner is next brought into contact with 10 part *d* of the cam which causes the corresponding binding warp thread to fall from the upper to the central position while the second runner comes into contact with part *g* of the second cam which raises the corresponding 15 binding warp thread to the upper position and opens the shed again above the central warp threads ready for the insertion of the second upper shot of weft. The stuffer or body warp threads 20 and the pile threads 4, remain throughout stationary in the central position except when the selected pile thread 4, is raised by the design producing mechanism. If desired, when the upper shots of weft are to be inserted, the binding warp thread beneath the said shot may be taken to the lower position instead of to the central position in which case the form of cam shown by Fig. 25 4 is not required, two ordinary cams being used instead of the two cams 6.

The weave of the fabric as above described is only given as an example to show how to avoid operating or raising and lowering the warp threads oftener than is absolutely necessary to produce said fabric, from which example those having a knowledge of this class of weaving will understand how the same benefits in the saving of power and the consequent unnecessary wear or deterioration, 30 may be secured in the production of other types or classes of fabric.

It will be observed that in order to carry out the weaving operations described it is necessary that there should be two shuttle races one of which is formed by the stationary warp threads 2 and those threads 4 parallel thereto as is hereinbefore described and the other beneath said central warp threads. This is preferably formed, either by the 45 slayboard or lay bottom B as shown by Fig. 1 or by grid like ribs or cross pieces B¹ as shown by Figs. 2 and 3. These pieces B¹ are fixed in or formed upon said lay bottom B in order that one and the same shuttle 5 may be made to travel through the shed or between the warp threads (in the order explained) by having a passage to pass through, which is of the desired shape to suit the angularity of the shuttle's walls.

60 The approved method which we follow in arranging for the actuating of the shuttles 5, 5^a over these two shuttle races consists in making use of a two cell shuttle box 7 and 7^a which we fix upon each end of the 65 slayboard or lay bottom B in the usual po-

sition that shuttle boxes occupy, the base of the upper cell 7 being in alignment with the shuttle race formed by the centrally situated warp threads while the base of the cell 7^a is in alignment with the upper surface of the slayboard or lay bottom B or the warp threads near same or with the grid like ribs B¹ as shown by Figs. 2 and 3 which are made use of for the purpose hereinafter explained.

In order to be enabled to throw or project the shuttles 5 and 5^a when arranged as above described, we make use of a picker carrying member 8 shown in detail Fig. 9 which will raise the picker 9 (when it reaches the outermost end of the lower cell 7^a) into position and to be in alignment with the upper cell 7 of the shuttle box as is shown by Figs. 5 and 7. Or by the lowering of said member 8 we may cause the picker 9 to descend from the position shown by Figs. 5 and 7 so that it may be brought into alignment with the lower cell 7^a of the shuttle box as is shown by Fig. 8. The raising and lowering of this member 8 from its lower to its higher and from its higher to its lower positions is effected by cam action.

The arrangement which we have found advantageous consists of the cam 10 (mounted on the same shaft as the cams 6 so that said cams work in unison) operating the lever 11 which by the rod 12 operates the lever 13 fixed to a shaft 14 upon which shaft 14 is fixed another lever 15 so that by an actuating rod 16 this latter lever 15 may operate a lever 17 fixed upon a shaft 18 extending from one side of the loom to the other. The shaft 18 has at each of its outer ends a lever 19 (shown by Figs. 5 and 7) fixed upon it, so that each of these levers 19 may be made to engage with a swivelling member 20. Through this swivelling member 20 a connecting rod 21 is made to slide when compressing the springs 22 and 23 as is herein-after described.

The rod 21 is pivotally connected to the member 8 so that when the cam 10 operates the levers above described the lever 19 will raise the swivelling member 20, causing it to press upon the spring 22 so that by this latter pressing upon the collar 22^a fixed on the rod 21, it will raise the member 8 to carry the picker 9 into alignment with the cell 7 in order that it may operate the shuttle 5.

When the lever 19 descends the member 20 is caused to press upon the spring 23 thus this latter will press upon the collar 23^a which is fixed upon the rod 21 by which means the rod 21 will move the member 8 from its higher to its lower position where it is in alignment with the cell 7^a so that the picker 9 may then operate the shuttle 5^a.

The springs 22 and 23 are employed in order to prevent breakage should the picker 9 be held against movement by being caught

between the partition α (which as shown in Fig. 8 divides the cell 7 from the cell 7^a) and the member 8 by reason of having only partly entered said member 8. During such events should the lever 19 be rising while the rod 21 is prevented from doing so, then the spring 22 will yield to permit the swivelling member 20 to rise. Whereas should the lever 19 be descending while the rod 21 is held against movement then the spring 23 will yield.

In order to ensure perfect alignment of the member 8 with the cells 7 and 7^a when operated by the rod 21 we arrange the lever 19 to transmit slightly more motion to the member 20 than is required by the member 8, thus when this latter reaches its highest position where it is arrested by the stop pieces 24 the slightly further movement of the lever 19 is permitted by the yielding of the spring 22. When the member 8 reaches its lowest position where it is arrested by the support B² then the yielding of the spring 23 permits the lever 19 to continue its downward movement a little further. These yielding movements of the springs 22 and 23 effect the adjustments of the member 8 accurately without requiring the accurate adjustment of the motions of the lever 19.

As is well known the order of picking the shuttles 5, 5^a has to be carried out in accordance with the requirements of the weave and to attain this object we make use of the formation of cams known as sectional cams upon which we may mount raising portions or depressing portions in manner well known and which are styled in the trade "Woodcroft" tappets or cams.

In order to guide the picker 9 along the cells 7, 7^a of the shuttle box we have guiding grooves 25 and 26 (see Fig. 8) formed in a member fixed to the end of the slayboard or shuttle box support B² so that the outer edge of the picker 9 may slide along said grooves 25 and 26 while the other part of the picker may pass along the grooves 25^a and 26^a formed respectively in the cells 7 and 7^a thus said picker is prevented from tilting and is guided in the desired manner for carrying out its respective functions of propelling the shuttle 5 along the race formed by the central warp threads or of propelling the shuttle 5^a along the race or path formed by the lay-bottom or slayboard B.

The arrangement of the picking mechanism which we employ is preferably of the "under pick" type as is shown by the drawings and when making use of this under pick type in conjunction with a slayboard which is mounted upon double layswords so that the cells 7, 7^a of the shuttle box are always kept in a vertical position notwithstanding their backward and forward movement, we then arrange the picking stick 27 to have its upper end 27^a pivoted upon it at b as shown

by Figs. 5, 7 and 8. This we find advantageous in order to keep the upper end 27^a of said picking stick 27 in alignment with a vertical plane parallel to the plane in which the cells 7 and 7^a are situated notwithstanding the difference of the oscillations of the lower ends of the picking sticks about one centre of oscillation of the layswords and the oscillations of the two cells 7 and 7^a which (by the employment of two pairs of layswords) are kept in a vertical position.

The picking mechanism we employ is operated by the picking strap 28 and may be of any well known description provided means are afforded by such picking mechanism for controlling the intermittent actions of the picking sticks 27 according to the requirements of the fabric that is being woven.

We have hereinbefore described a method of making use of two cells 7, 7^a for the two different shuttles 5 and 5^a with the member 8 which is arranged to slide and be guided at the outer end of said cells 7, 7^a in order to raise the picker 9 from one plane to another or to depress same from the upper plane to the lower as is described. In this arrangement we make use of two different shuttles one 5 having the contour of its outer surfaces at the desired angles to meet the requirements of the upper shuttle race whilst the other 5^a has its said surface at another angle to suit the requirements of the shuttle race formed by the slayboard or laybottom B as shown by Fig. 1. However, we may make use of one shuttle and arrange the shuttle box which receives same to rise and fall or be operated by any appropriate shuttle box operating mechanism mounted in position to move such shuttle box which is mounted to slide over the end B² of the slayboard in manner well known, instead of having the fixed cells 7, 7^a mounted thereon, thus in this latter case the shuttle box will be movable in a vertical direction to raise the shuttle from a lower position opposite the shuttle race on the lay B to the higher position opposite the shuttle race over the central warp threads at the same time also carrying with it the picker 9 which has to operate the shuttle.

To enable us thus to use one shuttle alone we arrange the lay B to have grid like ribs B¹ fixed upon it to form a suitable surface over which the shuttle has to pass as is shown by Figs. 2 and 3 and the angle formed by these ribs B¹ and the reed is the same as that formed by the central warp threads and the same reed.

Such being the nature of our invention what we claim is:

1. A loom comprising, in combination, means for guiding the body warp threads in a predetermined central substantially horizontal path and maintaining such threads without shedding movements, means for guiding binding warp threads in co-

operative relation to the body threads, means for raising and depressing said binding warp threads to form a shed with the body threads, a shuttle arranged to travel 5 from side to side through the shed over the body warp threads, another shuttle arranged to travel from side to side through the shed under the body warp threads, a stationary shuttle box, two cells on each 10 side of the loom to receive said shuttles, a picker arranged to actuate said shuttles, and means for raising and lowering said picker so that at one time it will be in position to throw the shuttle from the upper cell of the 15 shuttle box, and at another time will be lowered to throw the shuttle from the lower cell of the shuttle box.

2. A loom comprising, in combination, 20 means for guiding the body warp threads in a predetermined central substantially horizontal path, and maintaining such threads without shedding movement to serve as a shuttle race, means for raising and depressing binding warp threads to 25 form sheds, respectively, above and below said body threads, a shuttle adapted to travel from side to side through the shed above the body warp threads, another shuttle arranged to travel from side to side through 30 the shed under the body warp threads, a relatively stationary shuttle box having two superposed cells at opposite sides of the looms to receive said shuttles, a swinging picking stick, a picker mounted on the upper portion 35 of said stick and adapted to actuate said shuttles, and means for positively raising and lowering the picker on the picker stick so that at one time the picker will be in position to throw the shuttle from the upper stationary 40 cell of the shuttle box, and another time will be in position to throw the shuttle from the lower cell of the shuttle box.

3. A loom comprising, in combination, 45 means for guiding the body warp threads in a predetermined central substantially horizontal path, and maintaining such threads without shedding movement to serve as a shuttle race, means for raising and depressing binding warp threads to form

50 sheds, respectively, above and below said body threads, a shuttle adapted to travel from side to side through the shed above the body warp threads, another shuttle arranged to travel from side to side through the shed under the body warp threads, a 55 relatively stationary shuttle box having two superposed cells at opposite sides of the loom to receive said shuttles, a swinging picker stick, a picker mounted on the upper portion of said stick and adapted to actuate 60 said shuttles, and means for positively raising and lowering the picker on the picker stick including cushioning means for limiting the movement of the picker in either direction, so that at one time the picker will 65 be in position to throw the shuttle from the upper stationary cell of the shuttle box, and another time will be in position to throw the shuttle from the lower cell of the shuttle 70 box.

4. A loom comprising, in combination, 75 means for guiding the body warp threads in a predetermined central substantially horizontal path, and maintaining such threads without shedding movement, means for raising and depressing binding warp threads to form sheds, respectively, above and below 80 said body threads, a shuttle adapted to travel from side to side through the shed above the body warp threads, another shuttle arranged to travel from side to side through the shed under the body warp threads, a relatively 85 stationary shuttle box having two superposed cells at opposite sides of the loom to receive said shuttles, a swinging picking stick comprising two members pivotally connected, a picker embracing the upper pivotal section of the picking stick, means for moving said picker vertically so that at 90 one time it will be in position to throw the shuttle from the upper cell of the shuttle box, and at another time it will be lowered to throw the shuttle from the lower cell of the shuttle box, and spring means cushioning the vertical movement of the picker 95 in either direction.

JOHN ERNEST GROSVENOR.
WILLIAM THOMAS PICKING.
